THE NOORIS PAPER CO., SHOTGUN TINTO, WASHINGTON.

UNITED STATES PATENT OFFICE.

HENRY L. FERRIS, OF HARVARD, ILLINOIS, ASSIGNOR TO HUNT, HELM & FERRIS, OF SAME PLACE.

COMBINED CHURN AND BUTTER-WORKER.

SPECIFICATION forming part of Letters Patent No. 619,291, dated February 14, 1899.

Application filed March 7, 1898. Serial No. 672,808. (No model.)

To all whom it may concern:

Be it known that I, HENRY L. FERRIS, a citizen of the United States of America, residing at Harvard, in the county of McHenry and State of Illinois, have invented certain new and useful Improvements in a Combined Churn and Butter-Worker, of which the following is a specification.

My invention relates to certain improvements in combined churns and butter-workers; and it consists in certain features of novelty designed to render the same more rapid, efficient, and easy to operate and keep clean.

The invention is illustrated by means of three sheets of drawings containing six figures, of which—

Figure 1 is a vertical diametrical longitudinal section of the machine. Fig. 2 is a vertical cross-section in line 2 2 of Fig. 1, looking toward the drum or barrel. Fig. 3 is a similar section in line 3 3 of Fig. 1, looking in the same direction. Fig. 4 is a section in line 4 4 of Fig. 5, looking from left to right. Fig. 5 is a section at right angles to Fig. 4 in line 5 5 of the latter figure, and Fig. 6 is a partial view similar to Fig. 1 of a modified construction.

Referring first to Fig. 1, A A' are two brackets suitably supported and having journaled in their tops two gudgeons b b', secured to the opposite ends of a churn-barrel B, here shown as fastened to the gudgeons by means of bolts b². This barrel is provided upon its inside with a series of longitudinally-arranged inwardly-extending wings or ribs b³, the function of which is to agitate the cream in the churning operation and to coöperate with other devices to work the butter after it is churned. These ribs do not extend entirely to the barrel-heads, but are fitted at their ends to rings C C', substantially triangular in cross-section and themselves fitted into the corners of the barrel to prevent the butter from collecting in said corners and also to make the same easy to clean and keep in proper condition. In the inner surfaces of the gudgeons b b' are sockets b⁴ b⁵, in which is journaled a shaft D, having two links d d', secured upon it against rotation and prefer-

gether and with the shaft. In these two links is journaled a second shaft D', upon the opposite ends of which are hung two weighted arms E E', preferably secured against rotation upon the shaft D', and carrying at their free ends a third shaft F, also preferably secured against rotation in the sectors and which has journaled upon it a corrugated roller G.

The barrel is rotated by means of a driving-pulley H, mounted upon a shaft h, journaled in the bracket A' and carrying a pinion I, which meshes with an internal gear or annular rack J, secured to the adjacent head of the barrel.

The weight of the arms E E' is relied upon to keep the roller G in or near the bottom of the barrel and to return it thereto when forced out of such position by an accumulation of butter.

If, as in the preferable construction, the links d d' are secured against independent rotation or oscillation with respect to each other and the arms E E' are similarly secured with respect to each other, the axis of the roller G will be kept at all times parallel to that of the barrel, and yet the roller will be perfectly free to oscillate upon either of the two axes marked by the centers of the shafts D D'. The weight of the arms E E' tends to keep the links d d' in a vertical position, so that if the roller is carried around by the butter until it rises materially from the bottom of the tub such movement will gradually withdraw it from the inner surface of the barrel, tending to allow the butter to pass through, and, furthermore, the crowding action of the butter will tend to force the links d d' out of a vertical position toward the opposite side of the barrel from that occupied by the roller and carry said roller still farther from the walls of the barrel, thereby also aiding in the passage of the butter between the two.

In the operation of the machine as a churn the roller hangs downward, as seen in Figs. 1 and 3, and acts as a sort of stationary dasher to agitate the cream as the latter is thrown against it by the rotation of the barrel. As soon as the butter is churned the roller im-

mediately commences to work the same between it and the internal wings or ribs upon the barrel.

The advantages of my device I consider to be its great simplicity both in construction and in operation, together with the ease with which it may be taken care of and the efficiency with which it does its work.

The modification shown in Fig. 6 varies from 10 the construction shown in the other figures merely in the substitution of a short pin X for the shaft D' at each end of the machine to pivot the arms E E' upon the links d d'. In this case the arms E E' are secured against 15 independent oscillation by means of the shaft F, to which said arms are preferably keyed.

I claim as new and desire to secure by Letters Patent—

1. In a combined churn and butter-worker 20 the combination with a rotatable barrel, of a freely-oscillating weighted roller hung within the barrel adjacent to the inner surface thereof and upon an axis of oscillation eccentric to the axis of the barrel; substantially as described.

2. The combination in a combined churn and butter-worker of a rotating barrel, a shaft journaled in the barrel concentric with the axis thereof, a pair of links hung upon the 30 shaft adjacent to the opposite ends of the barrel, a pair of weighted arms pivoted, respectively to the respective links and a roller journaled between the free ends of the weighted arms and adjacent to the inner surface of the 35 barrel substantially as described.

3. The combination in a combined churn and butter-worker and with a rotating barrel, of a shaft journaled within the barrel concentric with the axis thereof, a pair of links 40 secured against rotation upon the shaft adjacent to the opposite ends of the barrel, a pair of weighted arms pivoted to the free ends of the links and themselves secured against independent oscillation with respect to each

other and a roller journaled between the free 45 ends of the arms and near the inner surface of the barrel; substantially as described.

4. In an apparatus of the class described, the combination with a suitably-mounted rotating barrel, of bearings within and at opposite 50 ends of the same, freely-oscillating links hung upon said bearings, connecting devices between said links preventing angular movement of one with respect to the other and a roller journaled between the free ends of said 55 links; substantially as described.

5. In an apparatus of the class described, the combination with a rotatably-mounted barrel, of bearings within and at opposite ends of the same, a pair of freely-oscillating links 60 pivoted at one end to said bearings, a second pair of freely-oscillating links pivoted at one end to the free ends of the first pair and a roller journaled between the free ends of the second pair; substantially as described.

6. In an apparatus of the class described, the combination with a rotating barrel, of bearings within and at opposite ends thereof, a pair of freely-oscillating links pivoted at one end to said bearings, connecting devices holding each of the links against angular movement, independent of the other, a second pair of freely-oscillating links pivoted at one end to the free ends of the first pair, connecting devices between the second pair of links preventing independent angular movements of one with respect to the other and a roller journaled between the free ends of the second pair of links; substantially as described.

In witness whereof I have hereunto set my 80 hand, at Chicago, in the county of Cook and State of Illinois, this 25th day of February, A. D. 1898.

HENRY L. FERRIS.
